CLAIM

The ornamental design for a vibrating bed board, as shown and described.

DESCRIPTION

FIG. 1 is a top, front and right-side perspective view on a reduced scale of a vibrating bed board showing my new design;

FIG. 2 is a top plan view thereof;

FIG. 3 is a right-side elevational view thereof, the left-side elevational view being a mirror image;

FIG. 4 is a bottom plan view thereof;

FIG. 5 is a front elevational view thereof; and

FIG. 6 is a rear elevational view thereof.

On FIGS. 2 to 4 the bed board portion is not shown in full for convenience of illustration.

FIG. 1.

FIG. 2.

FIG. 3.

FIG. 4.

FIG. 5.

FIG. 6.
